CLOCK FACE

Marion K. Summers, W. Commerce St., Brownstown, Ind. 47220, and Roy Lee Baker, Kural Route, Shipman, Ill. 62685

Continuation-in-part of design application Ser. No. 4,203, Oct. 10, 1966. This application Feb. 28, 1968, Ser. No. 10,769

Term of patent 14 years

Int. Cl. D10—06

U.S. Cl. D42—7

FIG. 1

FIG. 2

FIG. 1 is a front elevational view of a clock face showing our new design wherein the essential features reside in the portions shown in full lines and in the particular arrangement of postage stamp representations of increasing valuation as the hour pips, and

FIG. 2 is a top plan view thereof.

This application is a continuation-in-part of co-pending application, Ser. No. D.4,203, filed Oct. 10, 1966 now abandoned.

We claim:

The ornamental design for a clock face, substantially as shown and described.
